ABSTRACT OF THE DISCLOSURE

The invention relates to a method of producing peripheral vasodilation which comprise the oral or parenteral administration in unit dosage form of a compound having the formula:

where *n* is 1 or 2, *p* is 1 or 2, R, R¹ and R² represent specified radicals. The above compounds are preferably administered together with a pharmaceutically acceptable diluent or carrier therefor, in the form of a pharmaceutical composition.

This invention relates to pharmaceutical compositions and in particular to pharmaceutical compositions which may be used in the treatment of disorders of the cardiovascular system.

According to this invention there are provided pharmaceutical compositions comprising a compound of the formula:

in which

n is an integer 1 or 2,

p is an integer 1 or 2,

when *n*=1, R represents an alkoxy or alkyl group having 1 to 3 carbon atoms,

when *n*=2, (R)₂ represents alkoxy or alkyl groups having 1 to 3 carbon atoms, chlorine atoms or when attached to adjacent carbon atoms of the benzene ring the group

—O(CH₂)_mO— where *m* is an integer 1, 2 or 3, R¹ represents a hydrogen atom or when (R)_n represents at least one alkoxy group R¹ may also represent a chlorine atom, a bromine atom, an alkoxy or alkyl group having 1 to 3 carbon atoms, a nitro group, an amino group or a pharmaceutically acceptable salt of an amino group,

R² represents an alkyl group having 1 to 7 carbon atoms, an alkenyl or alkynyl group having 3 to 5 carbon atoms or a hydroxyalkyl group having 2 or 3 carbon atoms; together with one or more pharmaceutically acceptable diluents or carriers.

In particular the present invention provides pharmaceutical compositions comprising sulphoxides of the formula

2

in which R, R¹, R² and *n* are as hereinbefore defined together with one or more pharmaceutically acceptable diluents or carriers.

In particular the present invention provides pharmaceutical compositions comprising sulphones of the formula

in which R, R¹, R² and *n* are as hereinbefore defined together with one or more pharmaceutically acceptable diluents or carriers.

The invention also includes compounds of the formula

in which R¹ represents a hydrogen atom or a methoxy group, and R² represents an alkyl group having 1 to 7 carbon atoms, an alkenyl or alkynyl group having 3 to 5 carbon atoms, or a hydroxyalkyl group having 2 or 3 carbon atoms.

These compositions produce a significant reduction in blood pressure when administered to normotensive, DOCA or renal rats and also cats and dogs and have utility in the treatment of those conditions in man for which an anti-hypertensive or vasodilator drug is employed.

The pharmaceutical compositions may be in a form suitable for oral administration or in a form suitable for parenteral administration. Compositions intended for oral use may be in the form of tablets, packaged powder or granules, aqueous or oily suspensions, emulsions, hard or soft capsules, lozenges or syrups.

Compositions intended for oral use may be prepared according to any method known to the art for the manufacture of pharmaceutical compositions and such compositions may contain one or more sweetening, flavoring, coloring or preserving agents in order to provide pharmaceutically elegant and palatable preparations.

Tablets contain the compound of said formula in admixture with excipients which are suitable for manufacture of tablets. These excipients may be inert diluents, such as, calcium phosphate, lactose, sucrose or dextrose; granulating and disintegrating agents, such as starch or alginic acid; binding agents such as starch, gelatine or acacia; and lubricating agents such as magnesium stearate, stearic acid or talc.

Compositions for oral use in the form of hard gelatine capsules contain the compound of said formula mixed with an inert solid diluent such as calcium phosphate, lactose or kaolin, or as soft gelatine capsules in which the compound of said formula is mixed with an oily medium such as arachis oil, liquid paraffin or olive oil.

Compositions intended for parenteral administration may be in the form of sterile injectable preparations such as solutions or suspensions in water, saline or 1,3-butane diol. The preparations may also contain suitable wetting agents and suspending agents.

For the purposes of convenience and accuracy of dosing the compositions are advantageously employed in a unit dosage form. For oral administration the unit dosage form contains from 1 mg. to 500 mg., preferably from 10 mg. to 100 mg., of the compound of said formula. Parenteral unit dosage forms contain from 1 mg. to 10 mg. of the compound of said formula per 1 ml. of the preparation.

The compounds of said formula may be prepared by oxidizing the corresponding thioethers. The oxidation may be carried out employing as the oxidizing agent hydrogen peroxide, N-halosuccinimides, 1-chlorobenzo-triazole and other known chemical equivalents.

In the preparation of compounds of said formula in which $p=1$ (sulfoxides) suitable methods for carrying out this oxidation include the use of hydrogen peroxide in acetic acid, N-bromosuccinimide or N-chlorosuccinimide in methanol, and 1-chlorobenzotriazole in methanol or methylenechloride. In order to minimize the formation of a further oxidation product, namely the sulphone ($p=2$) an equimolar proportion of the oxidizing agent should be employed, and the oxidation conducted at 0–20° C.

In the preparation of compounds of said formula in which $p=2$ (sulphones) a convenient process for carrying out the oxidation is in acetic acid using a 2–3 fold excess of hydrogen peroxide and heating the mixture on a steam bath.

The thioethers used as starting materials may be readily prepared from thiols for example by treatment with an organo-halide or sulphate.

The following examples illustrate the preparation of compounds of said formula:

EXAMPLE 1

3,4-dimethoxyphenylmethyl sulphoxide

3,4-dimethoxythiophenol (28.3 g., 0.17 mole; A. A. Levi and S. Smiles. J. Chem. Soc. 520 (1931)) was added to sodium (3.83 g., 0.17 mole) in absolute ethanol. Dimethyl sulphate (20.8 g., 0.17 mole) was slowly added to the mixture which was then refluxed for two hours. The solvent was removed under reduced pressure. The residue was extracted with chloroform. The extracts were washed with water, dried over magnesium sulphate and evaporated to give 3,4-dimethoxyphenylmethyl sulphide (28.6 g.) B.P. 110° C./0.8 mm.

Analysis.—Calcd. for $C_9H_{12}O_2S$: C, 58.7; H, 6.6; S, 17.4%. Found: C, 58.5; H, 6.4; S, 17.2%.

30% hydrogen peroxide (11.3 ml., 0.1 mole) was added to the 3,4-dimethoxyphenylmethyl sulphide (18.4 g., 0.1 mole) in glacial acetic acid (100 ml.) with cooling. The mixture after remaining at room temperature for 24 hours was made alkaline by the slow addition of ice-cold aqueous sodium hydroxide. The mixture was extracted with chloroform. The extracts were washed with water, dried over magnesium sulphate and evaporated to dryness under reduced pressure to give white crystalline 3,4-dimethoxyphenylmethyl sulphoxide (15.1 g.). A sample recrystallized from diisopropyl ether had M.P. 82–84° C.

Analysis.—Calcd. for $C_9H_{12}O_3S$: C, 54.1; H, 6.1; S, 16.0%. Found: C, 53.9; H, 6.3; S, 15.7%.

EXAMPLE 2

3,4-dimethoxyphenylethyl sulphoxide

3,4-dimethoxythiophenol (8.6 g., 0.05 mole), sodium (1.15 g., 0.05 mole), ethanol (50 ml.) and ethyl iodide (7.8 g., 0.05 mole) were reacted according to the manner of Example 1 to give 3,4-dimethoxyphenylethyl sulphide (7.3 g.), B.P. 100–108° C./0.2 mm.

Analysis.— $C_{10}H_{14}O_2S$ requires: C, 60.7; H, 7.1; S, 16.2%. Found: C, 60.7; H, 7.0; S, 15.9%.

The 3,4-dimethoxyphenylethyl sulphide (1.98 g.) was oxidized, according to the manner of Example 1, to give 3,4-dimethoxyphenylethyl sulphoxide (1.6 g.).

Analysis.—Calcd. for $C_{10}H_{14}O_3S$: C, 56.1; H, 6.6%. Found: C, 56.0; H, 6.4%.

EXAMPLE 3

3,4-dichlorophenylmethyl sulphoxide

(a) 3,4-dichlorothiophenol (8.9 g., 0.05 mole; S. M. Dandin et al. Chem. Abs. 52, 8071), sodium (1.15 g., 0.05 mole), ethanol (50 ml.) and methyl iodide (7.1 g., 0.05 mole) were reacted according to the manner of Example 1 to give 3,4-dichlorophenylmethyl sulphide (7.2 g.), B.P. 76–80° C./0.2 mm.

The 3,4-dichlorophenylmethyl sulphide (5.7 g., 0.03 mole) was dissolved in dry methanol (80 ml.) and cooled to 0° C. in an ice-bath. N-chlorosuccinimide (4 g., 0.03 mole) was added in increments whilst keeping the temperature below 10° C. The mixture was allowed to stand for an hour. The solvent was removed under reduced pressure. The residue was extracted with chloroform. The extracts were washed with water, dried over magnesium sulphate and evaporated to give a white oil, which on trituration with light petroleum ether afforded crystalline 3,4-dichlorophenylmethyl sulphoxide (4.8 g.) M.P. 72–74° C.

Analysis.—Calcd. for $C_7H_6Cl_2OS$: C, 402.2; H, 2.9; Cl, 34.0; S, 15.3%. Found: C, 39.7; H, 2.7; Cl, 34.2; S, 15.8%.

(b) The 3,4-dichlorophenylmethyl sulphide (4.0 g., 0.03 mole) was dissolved in dry methylene chloride (50 ml.) and cooled to –78° C. in a Dry Ice/alcohol bath. 1-chlorobenzotriazole (3.6 g., 0.03 mole) was added and the mixture was allowed to warm to room temperature (45–60 minutes). The mixture was washed successively with 10% aqueous sodium hydroxide then water, and finally dried over magnesium sulphate. The solvent was evaporated off under reduced pressure, to give a produce (3.5 g.) M.P. 72–74° C., identical to that obtained in (a) above.

EXAMPLE 4

2,5-dimethoxyphenylmethyl sulphoxide

2,5-dimethoxythiophenol (2.8 g., 0.017 mole; Suter and Hansen J. Am. Chem. Soc. 54, 4102 (1932)) was added to sodium (0.4 g., 0.017 mole) in absolute ethanol. Dimethyl sulphate (2.1 g., 0.017 mole) was slowly added to the mixture which was then refluxed for two hours. The solvent was removed under reduced pressure. The residue was extracted with chloroform. The extracts were washed with water, dried over magnesium sulphate and evaporated to give 2,5-dimethoxyphenylmethyl sulphide (2.8 g.) B.P. 92–96° C./0.3 mm.

Analysis.—Calcd. for $C_9H_{12}O_2S$: C, 58.7; H, 6.6; S, 17.4%. Found: C, 59.0; H, 6.5; S, 17.5%.

The 2,5-dimethoxyphenylmethyl sulphide (2.3 g.) was oxidized according to the manner of Example 1 to give 2,5-dimethoxyphenylmethyl sulphoxide (1.8 g.) M.P. 70–72° C.

Analysis.—Calcd. for $C_9H_{12}O_3S$: C, 54.1, H, 6.1; S, 16.0%. Found: C, 53.5; H, 6.0; S, 16.5%.

EXAMPLE 5

3,4-dimethoxyphenylmethyl sulphone

3,4-dimethoxyphenylmethyl sulphide (6.1 g., 0.03 mole) and 30% hydrogen peroxide (11.3 ml., 0.1 mole) were heated on a steam bath for 2 hours in glacial acetic acid (100 ml.). The mixture was poured onto ice (300 g.) and the resulting white precipitate filtered, washed well with water and recrystallized from ethanol to give 3,4-dimethoxyphenylmethyl sulphone (5.7 g.), M.P. 115–117° C.

Analysis.—Calcd. for $C_9H_{12}O_4S$: C, 50.0; H, 5.6; S, 14.8%. Found: C, 49.8; H, 5.8; S, 14.7%.

EXAMPLE 6

3,4-dimethoxy-6-nitrophenylmethyl sulphone

3,4-dimethoxyphenylmethyl sulphone (6.5 g., 0.03 mole) was dissolved in concentrated nitric acid (20 ml.) and allowed to stand at room temperature for 1 hour. The mixture was poured onto ice and the yellow precipitate filtered off and recrystallized from ethanol to give 3,4-dimethoxy-6-nitrophenylmethyl sulphone (5.8 g.), M.P. 186–188° C.

Analysis.—Calcd. for $C_9H_{11}NO_6S$: C, 41.4; H, 4.2; N, 5.4; S, 12.3%. Found: C, 41.4; H, 4.1; N, 5.4; S, 12.3%.

5
EXAMPLE 7

6-amino-3,4-dimethoxyphenylmethyl sulphone

3,4-dimethoxy-6-nitrophenylmethyl sulphone (4.0 g.), was dissolved in acetic acid (100 ml.) and stannous chloride (20 g.) in concentrated hydrochloric acid (20 ml.) added. The mixture was heated on a water bath for $\frac{1}{2}$ hour, the acetic acid was evaporated off under reduced pressure, and the aqueous layer was basified with dilute aqueous sodium hydroxide and extracted with chloroform. The chloroform extracts were dried over magnesium sulphate and evaporated to give a yellow oil which solidified on standing. The product was recrystallized from ethanol to give 6-amino-3,4-dimethoxyphenylmethyl sulphone (1.4 g.), M.P. 97–98° C.

Analysis.—Calcd. for $C_9H_{13}NO_4S$: C, 46.8; H, 5.7; N, 6.1; S, 13.9%. Found: C, 46.9; H, 5.6; N, 6.2; S, 13.8%.

The table below sets out details of further examples of compounds of said formula. The compounds in which $p=1$ (sulphoxides) were prepared by the method of Example 1, and those in which $p=2$ (sulphones) were prepared by the method of Example 5.

6
EXAMPLE I

A mixture of 1 part of 3,4-dimethoxyphenylmethyl sulfoxide, 5 parts of lactose and 5 parts of starch, together with 1% of magnesium stearate was compressed into tablets. Conveniently the tablets are of such a size as to contain 10 or 25 mg. of 3,4-dimethoxyphenylmethyl sulfoxide. Similarly tablets containing 50 mg. of 3,4-dimethoxyphenylmethyl sulfoxide were prepared from a mixture of 2 parts of the sulfoxide, 5 parts of lactose, 5 parts of starch together with 1% magnesium stearate.

EXAMPLE II

A mixture of 1 part of 3,4-dimethoxyphenylmethyl sulfoxide, and 9 parts of a tablet base comprising starch with the addition of 1% magnesium stearate was compressed into tablets.

Conveniently the tablets are of such a size as to contain 10 or 25 mg. of 3,4-dimethoxyphenylmethyl sulfoxide.

EXAMPLE III

Various strength capsules are prepared containing 3,4-dimethoxyphenylmethyl sulphoxide and the following ingredients (amounts are in mg.):

Sulphoxide	Magnesium stearate	Calcium phosphate	Lactose
10	2	190	
25	2	175	
50	3	150	
100	3	100	
10		170	
25		155	
50		130	
100		80	

The above ingredients may be screened through a 40 B.S.S. mesh screen before being mixed and filled into hard gelatin capsules.

EXAMPLE IV

Ampoules were prepared containing 5 mls. of an isotonic solution prepared from 1 gm. 3,4-dimethoxyphenylmethyl sulphoxide and 0.735 gm. sodium chloride in 100 mls. distilled water. The solution was stable to steam autoclaving at 10 p.s.i. for 35 minutes.

EXAMPLE V

The 3,4-dimethoxyphenylmethyl sulphoxide in each of the foregoing Examples I-IV may be replaced by

2,4-dimethoxyphenylmethyl sulphoxide,
3,4-dimethoxyphenylethyl sulphoxide,
2,5-dimethoxyphenylmethyl sulphoxide,
6-amino-3,4-dimethoxyphenylmethyl sulphone,
3,4-dimethoxyphenylmethyl sulphone,
2,5-dimethoxyphenylmethyl sulphone,
3,4-dimethoxyphenylpropyl sulphoxide,
3,5-dichlorophenylmethyl sulphoxide,
3,4,6-trimethoxyphenylmethyl sulphoxide,
3,5-dimethoxyphenylmethyl sulphoxide, or
3,4-diethylphenylmethyl sulphoxide.

Screening for antihypertensive activity has been carried out employing known pharmacological tests such as those using normotensive, DOCA and renal hypertensive rats according to the method of Stanton, H. C., and White, J. B., Archs. Int. Pharmacodyn. Ther. 154, No. 2, 351 (1966) and Weeks, J. R., and Jones, J. A., Proc. Exper. Biol. & Med. 104, No. 4, 646 (1960).

The following are some of the test results obtained with compounds of said formula. The compounds were administered intraperitoneally at a dose of 100 mg./kg. to groups of DOCA hypertensive rats, and the figures are for the maximum percentage fall in the blood pressure.

No. of Example:	Percent fall in blood pressure
1	65
2	50
4	46
5	59
7	58
8	30
33	50
38	44
41	49
46	51

The following are some of the results when compounds were administered orally to groups of DOCA hypertensive rats at dosage levels of 20, 50 and 100 mg./kg. At each dose level a group of 6 rats was employed for each compound. The figures are for the maximum percentage fall in the blood pressure.

Dose (mg./kg.)	Percent fall in blood pressure		
	20	50	100
10			
No. of Example:			
1	30	36	53
2	21	34	50
4	5	14	21
5	33	41	50
8	16	28	42
14	18	18	26
15	24	28	44

It is expected that the likely human oral dose of a composition of the invention will be 200-500 mg. of active ingredient per day for the relief of hypertension.

It has been shown that these compounds possess interesting and prolonged vasodilator actions which are exerted on the smooth muscle fibres of the blood vessels of the peripheral circulation. There is no action on the autonomic nervous system. That the vasodilator activity is of peripheral origin is demonstrated by the following findings:

(1) The compounds have hypotensive activity in spinalized cats and pithed rats.

(2) The compounds are active against vasoconstriction produced by noradrenaline and vasopressin in a variety of isolated perfused blood vessel preparation e.g. rabbit ear, rat mesenteric vessels.

Further the compounds antagonize the pressor effects of noradrenaline, tyramine and angiotensin in the anaesthetized cat and dog at 3 to 10 mg./kg. inciting membrane contractions were also antagonized.

We claim:

1. Compounds of the formula:

(I)

in which R¹ represents a hydrogen atom or a methoxy group, and R² represents an alkyl group having 1 to 7 carbon atoms, an alkenyl or alkynyl group having 3 to 5 carbon atoms, or a hydroxyalkyl group having 2 or 3 carbon atoms.

2. 3,4-dimethoxyphenylmethyl sulphoxide.

3. 3,4-dimethoxyphenylpropyl sulphoxide.

4. 3,5-dimethoxyphenylmethyl sulphoxide.

5. 3,4-diethoxyphenylmethyl sulphoxide.

6. 3,4,6-trimethoxyphenylmethyl sulphoxide.

7. 2-methyl-4,5-dimethoxyphenylmethyl sulphoxide.
